WELDING ROD HOLDER

James H. Hill, Redondo Beach, Calif., assignor of
forty-nine per cent to Howard F. Craven,
Redondo Beach, Calif.

Application May 6, 1943, Serial No. 485,901

3 Claims.

(Cl. 219—8)

This invention relates to new and useful improvements in welding rod holders, the principal object of the present invention being to provide a holder which is used for holding large or small welding rods.

Another important object of the invention is to provide a holder of the character described in which rods can be easily inserted and held and from which the rods can be readily disconnected when they have been used to the extent desired.

Other objects and advantages of the invention will become apparent to the reader of the following description.

In the drawings—

Figure 1 represents a side elevational view.
Figure 2 is a longitudinal sectional view.

Figure 3 is a cross section on the line 3—3 of Figure 2.

Figure 4 is a cross section on the line 4—4 of Figure 2.

Figure 5 is a cross section on the line 5—5 of Figure 2.

Figure 6 is a perspective view of the clamp.
Figure 7 is a perspective view of the trigger.

Referring to the drawings wherein like numerals designate like parts, it can be seen that the present invention consists of a handle portion 5 having an obliquely disposed nose portion 6, these portions being integral and divided longitudinally into a pair of sections *a*, *a*.

Numeral 7 denotes a cable which has its bare end 7a suitably secured into a recess in the butt end of the handle portion 5. The sections of the portions 5, 6 are secured together by screws or the like 8 and the portion 5 has a substantially L-shaped recess 9 which substantially receives the trigger structure shown in Figure 7. This trigger consists of an arcuate-shaped arm 10 having a foot portion 11 which is embedded in a block 12 which defines a handle or trigger which can be operated by the fingers of a person holding the device by the handle 5.

The nose portion 6 has a longitudinally extending bore 13 in which a clamp element is located. This element consists of an elongated stem 14 projecting from a head structure 15, this head having a groove 16 extending transversely in one side thereof and a sloping portion 17 merging with a reduced extension 18. The stem 14 extends longitudinally through the bore 13 and through a smaller bore 19, the inner end thereof being bifurcated as at 20 to straddle the intermediate portion of the arm 10. A securing element is disposed through bifurcated portion 20 of the stem 14 and through an opening 21 in the

arm 10. A coiled compression spring 22 is interposed between the head 15 and the inner end of the bore 13.

Extending into the forward end of the nose portion 6 and being slightly offset with respect to the bore 13 is a short bore 23 for receiving a small gauge welding rod A.

As can be seen in Figure 2, a ball 24 is provided in the forward end of the bore 13 and rides the sloping portion 17 of the clamp element 15. The inner end of a rod A overlies this ball 24, and obviously the purpose of the spring 22 is to urge the head 15 forwardly so that the sloping portion 17 will urge and maintain the ball 24 in an upward position against the inner end of the rod A, thus securing the rod to the holder.

Furthermore, the nose portion 6 of the holder has an obliquely disposed bore 25 extending upwardly therein from the bottom thereof and as is apparent in Figure 2, the head 15 is registrable as far as the groove 16 is concerned with the bore 25, that is, when the trigger 10, 12 is moved upwardly. Obviously, when a welding rod B is inserted into the bore 25 and through the groove 16, and the trigger subsequently released, the spring 22 will urge the head 15 forwardly and thus clamp the rod B firmly in position.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A welding rod holder comprising a body having an elongated handle portion and an elongated nose portion rigid with and extending at an angle from the outer end of said handle portion, said nose portion having a main longitudinal bore and a second short bore opening through the outer end of the nose and communicating at one side with the outer portion of said main bore, said short bore being adapted to receive an end 40 of a welding rod, a head slidable in the main bore and having a stem projecting inwardly therefrom, said head having a sloping front portion provided with a forward reduced extension, a ball disposed on the inclined portion of the head, a spring in the main bore acting on the head to force the latter forwardly so as to cause the sloping portion of the head to move the ball laterally into gripping engagement with the welding rod, and manually operable means associated with the handle portion and connected with the inner

end of the stem for retracting the head and releasing the ball from the welding rod.

2. A welding rod holder comprising a body having an elongated handle portion and an elongated nose portion rigid with and extending at an angle from the outer end of said handle portion, said nose portion having a main longitudinal bore and a second short bore opening through the outer end of the nose and communicating at one side with the outer portion of said main bore, said short bore being adapted to receive an end of a welding rod, a head slideable in the main bore and having a stem projecting inwardly therefrom, said head having a sloping front portion provided with a forward reduced extension, a ball disposed on the inclined portion of the head, a spring in the main bore acting on the head to force the latter forwardly so as to cause the sloping portion of the head to move the ball laterally into gripping engagement with the welding rod, and manually operable means associated with the handle portion and connected with the inner end of the stem for retracting the head and releasing the ball from the welding rod, said handle portion having a recess including a rear part extending longitudinally of and in the under side of the handle portion and a forward part extending upwardly in said handle portion, said manually operable means including an angular trigger having an arm pivoted and mov-

able in the forward part of said recess and another arm coincident with and partly housed in the rear portion of said recess.

3. A welding rod holder comprising a body having an elongated handle portion and an elongated nose portion rigid with and extending at an angle from the outer end of said handle portion, said nose portion having a main longitudinal bore and a second short bore opening through the outer end of the nose and communicating at one side with the outer portion of said main bore, said short bore being adapted to receive an end of a welding rod, a head slideable in the main bore and having a stem projecting inwardly therefrom, said head having a sloping front portion provided with a forward reduced extension, a ball disposed on the inclined portion of the head, a spring in the main bore acting on the head to force the latter forwardly so as to cause the sloping portion of the head to move the ball laterally into gripping engagement with the welding rod, and manually operable means associated with the handle portion and connected with the inner end of the stem for retracting the head and releasing the ball from the welding rod, said handle and nose portions comprising longitudinal half-sections having the bores and the recess partly formed in each of the same, and means securing said half-sections together.
